UNITED STATES PATENT OFFICE.

RUFUS L. ANDERSON, OF PLANT CITY, FLORIDA.

BRUSH.

1,022,920.

Specification of Letters Patent.

Patented Apr. 9, 1912.

Application filed October 12, 1911. Serial No. 654,261.

To all whom it may concern:

Be it known that I, RUFUS L. ANDERSON, a citizen of the United States, residing at Plant City, in the county of Hillsboro and 5 State of Florida, have invented new and useful Improvements in Brushes, of which the following is a specification.

This invention relates to brushes and particularly tooth and analogous brushes, and 10 embodies a bristle element or member surrounded by a rubber tooth member to provide a combined cleaning and massaging brush for removing accumulations from the teeth and at the same time treating soft 15 gums to harden the latter, the brush being capable of being used in either right or left positions with the same operation. The improved brush is also aseptic in that the parts thereof are associated in such manner as to obviate the formation of crevices or projecting edges, thus providing for readily 20 cleaning the same. The parts of the improved brush are also positively associated in a commercially advantageous manner and may be economically produced.

The invention consists in the construction and arrangement of the several parts which will be more fully hereinafter described and claimed in preferred form.

30 In the drawings: Figure 1 is a perspective view of a brush embodying the features of the invention. Fig. 2 is a transverse vertical section through the brush. Figs. 3, 4 and 5 are detail views of the parts of the brush shown in cross-section and dissociated. Figs. 6, 7 and 8 are plan views of the parts of the brush.

The numeral 5 designates a back which 40 may be of any suitable form and material, aluminum or celluloid being found to be the preferable materials; and continuing from the back or secured thereto is a handle 6 of the same or other material. The back 5 is formed with a stock seat or recess 7 which in the present instance is of elongated or rectangular contour with rounded ends, though this form may be varied at 45 will. The material surrounding the upper edge or margin of the seat 7 is reduced to provide a securing flange 8 of angular form which is swaged inwardly to hold the brush material within the seat in a manner which 50 will be presently explained.

The brush elements comprise a stock 9 of celluloid, bone or other suitable material having bristles 10 secured therein by any

well known or approved means and projecting a suitable distance therefrom. The stock 9 is peripherally surrounded by a plurality of outstanding projections or fingers 11 which have recesses 12 between them, the outer ends of the fingers having their upper portions downwardly beveled as at 13. The projections or fingers 11 are of such length and general contour as to snugly fit in the 60 seat 7 of the back 5, and as clearly shown by Fig. 3 the projections or fingers 11 have their lower sides above the lower side of the stock 9 or are in offset relation to the latter so that a space 14 is 65 formed around the stock 9 under the said projections or fingers. It will be understood that the stock 9 is of materially less width than the width of the seat 7, but together with the projections or fingers 11 the 70 said stock is of such dimensions as to snugly fit against the side and end walls of the seat. The remaining brush element consists of a rubber annulus 15 of the same peripheral contour as the seat 7 and having 75 an opening 16 therein to snugly receive the stock 9, the said annulus having rubber brush members or teeth 17 projecting therefrom and of a length approximately equal to that of the bristles 10 so that the free 80 ends thereof will be flush with the free ends of the bristles. The body of the annulus 15 has a cross-sectional extent or width equal to the distance between the opposite 85 sides of the stock 9 and the free ends of the 90 projections or fingers 11 so that there will be a full engagement of the under sides of the said fingers or projections with the annulus body when the elements of the brush are associated in the seat 7.

95 In associating the parts of the brush the annulus 15 is placed in the seat 7 with the stock 9 in the opening 16 and the projections or fingers 11 extending over the body of the annulus. In this condition the rubber brush 100 members or teeth 17, which as shown are in transversely aligned pairs on opposite sides, will be located snugly within the recesses 12 between the projections or fingers 11 and fully surround the bristles 10. After the 105 brush elements have been thus associated the flange 8 is struck or swaged inwardly against the upper bevels 13 of the projections or fingers 11 and the latter, together with the stock 9, are forced downwardly 110 with firmness and positiveness into the seat, and as the maximum pressure is exerted on

the projections or fingers and the latter engage the upper side of the annulus 15 the said annulus will be tightly held and all crevices will be closed. In swaging the 5 flange 8 inwardly care will be taken to avoid the formation of shoulders or projections, as shown by Fig. 2, or the upper side of the said flange and of the adjacent edge portion of the back 5 will be flush with the upper 10 sides of the projections or fingers 11. By thus carefully associating the parts of the brush an aseptic device of this character is provided, there being no crevices or openings or shoulders for the collection of germs 15 or dirt at any point.

The brush consisting of the inner bristles 10 and outer surrounding rubber brush members or teeth 17 has been particularly devised for use as a combined cleansing and 20 massaging brush, and in the use of this brush material benefits will accrue by reason of the fact that the bristles are shielded and prevented from having contact with the gums, the latter being engaged wholly by 25 the yielding rubber brush members or teeth 17 with a massaging effect, and by this means tender or soft gums will be strengthened and hardened and at the same time the bristles 10 will be held upon the surface of 30 the teeth for cleansing purposes. The brush may be used either in right or left position with the same advantages.

It is proposed to make the brush in 35 various sizes and of different shapes, both as to peripheral and surface contours, and in view of the comparative simplicity of the brush embodying the cleansing and massaging features the cost of manufacture is materially reduced, especially in view of the 40 fact that the brush elements are secured within the back by the simple swaging operation of the flange 8 inwardly over the projections or fingers 11 and both parts of the brush elements thereby simultaneously 45 and accurately disposed within the back.

What is claimed is:

1. In a brush, the combination of a back, 50 a stock carrying bristle members, and rubber brush members having a supporting base structurally independent of and held in the back by the stock and surrounding the periphery of the bristle members, a part of the back being projected inwardly and engaging the edge of the stock to secure the 55 bristle and rubber members in place.

2. In a brush, the combination of a back, 60 a stock disposed in the back and carrying bristle members, and a rubber annulus carrying brush members surrounding the bristle members and having portions of the edge of the stock extending over and bearing 65 thereon.

3. In a brush, the combination of a back

having a seat therein, a stock carrying bristle members and provided with peripheral 65 outstanding projections with spaces therebetween, and a rubber annulus surrounding the stock beneath the projections and having brush members projecting through the spaces and surrounding the bristle members, 70 the stock and annulus completely filling the seat of the back and secured by a portion of the latter engaging the projections.

4. In a brush, the combination of a back 75 having a seat therein, a stock carrying bristle members, and a double row of rubber brush members surrounding the bristle members and having carrying means independent of the stock and over which portions of the stock extend within the seat. 80

5. In a brush, the combination of a back, a stock carrying bristle members, and a rubber annulus surrounding and located beneath the edge portion of the stock and interposed between the latter and the sides 85 and ends of the seat and having brush members extending upwardly through portions of the stock and completely surrounding the bristle members.

6. In a brush, the combination of a back 90 having a seat therein with a flange surrounding the margin of the same, a stock disposed in the seat and carrying bristle members, and a rubber annulus surrounding a portion of the edge of the stock and having brush members projecting upwardly through the latter and completely surrounding the bristle members, portions of the stock projecting over the annulus and having the flange of the back bent inwardly 95 thereagainst.

7. In a brush, the combination of a back having a seat therein with a flange surrounding the margin thereof, a rigid stock 100 having a plurality of projections surrounding the periphery thereof with spaces therebetween, the upper portions of the ends of the projections being downwardly beveled, and a rubber annulus surrounding the stock 105 beneath the projections and having rubber brush members extending upwardly through the projections, the stock having bristle members located within the rubber brush members, the stock and annulus being secured in the back by bending the flange of 110 the latter inwardly against the beveled ends of the projections and forming a flush joint with the upper surfaces of the said projections.

In testimony whereof I have hereunto set 115 my hand in presence of two subscribing witnesses.

RUFUS L. ANDERSON.
